UNITED STATES PATENT OFFICE.

ALEXANDER KONOFF, OF NEW YORK, N. Y., ASSIGNOR TO OVERLAND METAL NOVELTY CO. INC., OF NEW YORK, N. Y., A CORPORATION OF NEW YORK.

SUPPORTING DEVICE FOR ARTIFICIAL EYES.

Application filed March 19, 1924. Serial No. 700,372.

This invention relates to a supporting device for artificial eyes such as are used in the manufacture of children's dolls and the like.

5 It is now common practice to make these eyes as a pair of suitably ornamented spherical members mounted upon a carrying rod which is supported interiorly of the doll's head upon a suitable bracket and to connect 10 a weighted lever with this rod so that the rod and eyeballs will be oscillated back and forth as the doll is moved from upright to reclining position.

In the manufacture of dolls' heads it appears to be quite impractical, if not impossible, to make a number thereof of exactly the same shape and proportion, and this is particularly true with respect to the 15 sockets into which the eyeballs are intended 20 to fit. On this account various means have been provided for enabling convenient adjustment of the eyeballs with respect to each other upon their supporting rod so that the eyeballs may be made to properly cooperate 25 with the sockets of different heads.

In many of these devices the bracket upon which the carrying rod is supported has been held in position by being cemented to the material of the doll's head, and, in many 30 instances it has been found that the cement used, in drying and hardening has resulted in a certain amount of distortion of the doll head sufficient in many cases to cause the eyeballs to bind against the walls of their 35 sockets.

It is an object of the present invention therefore to provide a bracket, and a means of adjustment therefor by which the use of cement is eliminated and by which no occasion is given for any distortion of the doll 40 head or eye sockets due to the presence of said bracket or its attaching means, and a further object is to so construct the bracket that it may be readily and efficiently adjusted, after attachment, to properly seat the eyeballs in their respective sockets.

A more detailed object is to provide a bracket designed to be held in position within the doll's head by a suitable retaining bolt, and comprising means whereby, after the bracket has been set and its fastening bolt fully applied, spaced portions of the bracket may be individually adjusted to bring the adjacent respective eyeball into a proper fitting relation with its socket.

Other objects and aims of the invention, more or less specific than those referred to above, will be in part obvious and in part pointed out in the course of the following description of the elements, combinations, 60 arrangements of parts and applications of principles, constituting the invention, and the scope of protection contemplated will be indicated in the appended claims.

In the accompanying drawings which are 65 to be taken as a part of this specification, and in which I have shown merely a preferred form of embodiment of the invention:—

Figure 1 is a vertical sectional view 70 through a doll's head having eyes and a supporting bracket therefor constructed in accordance with this invention.

Figure 2 is a horizontal sectional view taken substantially upon the plane of II—II 75 of Fig. 1.

Figure 3 is a vertical sectional view taken substantially upon the plane of III—III of Fig. 1.

Referring to the drawings for describing 80 in detail the structure therein illustrated, the reference character L indicates the doll's head having the usual eye sockets 2 and 3 therein. The eyeballs are indicated by the reference character G and are shown to be 85 carried upon a common supporting rod 4 which is mounted in bracket H and to which is connected the usual weighted lever 5.

The rod 4 is adapted to oscillate in spaced 90 bearings 6 provided by the bracket H under the influence of the lever 5 whenever the doll is moved from an upright to a reclining position, and vice versa.

It will be apparent that the eyeballs although requiring to have a proper close fit 95 with the sockets 2 and 3 must nevertheless be sufficiently clear of engagement with the walls of said sockets so that no impediment will be offered to the free movement of the eyeballs whenever the doll is moved.

The bracket H comprises an upper plate 7 from which depends an extension 8 to which the rod 4 is connected. The plate 7 has at its upper end an opening 9 through which extends a bolt 10. This bolt is carried in an opening 11 formed through the material of the doll head at the top of the forehead portion thereof and its outer end is preferably concealed beneath the scalp part as 12, of the doll head.

The purpose of this bolt is to hold the upper end portion of the plate 7 rigidly connected with the adjacent portion of the doll head, and to this end the drawing illustrates 5 the use of a nut 13 at the inner end of the bolt disposed for pressing an interposed washer 14 against the inner face of the plate and for thereby clamping the plate against the material of the doll head.

- 10 In applying this device it is customary to lay the bracket, with its supported eyeballs, against the inner surface of the doll head and to first adjust the eyeballs longitudinally of the rod 4 so that they will rest snugly 15 into the sockets 2 and 3. When this is done the opening 9 of the plate 7 should register with the opening 11 of the doll head, and on this account the opening 9, as illustrated, is made considerably larger than the opening 20 11 and bolt 10, and the washer 14 is made in such proportions as to straddle the opening 9 and to thereby serve as an efficient clamp element between the nut and plate 7.

This washer 14 is also preferably made so 25 as to be slightly resilient for thereby providing a certain amount of resiliency in the structure so that the tightening of the nut will not be likely to injure the material of the doll head, while yet permitting a slight 30 movement of the plate relative to the head upon occasion.

Suitable projections 15 may be provided upon the plate adjacent to the opening 9 for being forced into the material of the doll 35 head, when the nut is screwed home, to prevent accidental movement of the plate with respect to the doll head.

Spaced downwardly from the plane of the fastening bolt 10 is a pair of adjusting 40 screws 16 and 17 carried by the plate and disposed one adjacent each of the eyeballs G. These screws extend through threaded apertures 18 provided in the plate and have their inner or forward ends arranged for engaging 45 against the adjacent inner surface portions of the doll head whereby inward or forward adjustment of the screws will operate to spring or bend the plate back for lifting the respective eyeballs free of engagement with 50 the walls of their sockets.

By disposing these screws spaced apart and in close proximity to the respective eyeballs it is possible to lift either of the eyeballs independently of its neighbor. If one eyeball continues to bind against its socket walls it is simply necessary to rotate the adjacent screw and thereby lift that particular eyeball free.

55 The resilient character of the plate 7 will permit the easy backward movement of the eyeballs by means of these screws and yet will at all times thereafter exert a sufficient resilient pressure against the screws and of the screws against the opposing doll head 60 surfaces, to prevent any unintentional rota-

tion or consequent failure of adjustment, of the screws.

Having thus described my invention, what I claim as new and desire to secure by Letters Patent is:—

70 1. A supporting device for doll eyes comprising a bracket adapted for carrying the eyes in the usual manner, means for fixing the bracket within a doll head, and means carried by the bracket associated with said eyes independently of each other and being manually adjustable upon the bracket for thereby adjusting the eyes independently of each other with respect to the doll head.

75 2. A supporting device for doll eyes comprising a bracket for carrying the eyes in the usual manner, means for fixing the bracket within a doll head, said bracket being flexible, and a pair of adjusting screws carried by the bracket one adjacent each of the eyes 80 having parts arranged to engage adjacent portions of the doll head whereby to adjust the eyes independently with respect to the doll head.

85 3. A supporting device for doll eyes comprising a bracket adapted for carrying the eyes in the usual manner, said bracket being flexible, means for fixing the bracket within a doll head interengaging between the doll head and a portion of the bracket spaced 90 relatively far from the eyes, and means relatively closer to the eyes associated with the eyes independently of each other and being manually operable to flex the bracket for thereby adjusting the eyes independently of 95 each other with respect to the doll head.

100 4. A supporting device for doll eyes comprising a plate to which the eyes are connected and which has a part adapted to rest against the inner surface of the doll head 105 when the eyes are arranged in their sockets, means for fixing said mentioned part of the plate within the doll head, and a pair of screws carried by another part of the plate spaced away from each other one adjacent 110 each eye being rotatably adjustable to adjust the relation of the eyes to their sockets respectively.

115 5. A supporting device for doll eyes comprising a plate to which the eyes are connected and which has a part adapted to rest against the inner surface of the doll head when the eyes are arranged in their sockets, means for fixing said mentioned part of the plate within the doll head, said plate being 120 flexible, and a pair of manually operable devices one adjacent each of the eyes operable to flex the plate and to thereby adjust the position of the eyes respectively with relation to their sockets.

125 6. A supporting device for doll eyes comprising a plate to which the eyes are connected and which has a part adapted to rest against the inner surface of the doll head 130 when the eyes are arranged in their sockets.

- a bolt carried by the doll head, said mentioned part of the plate having an opening therethrough to receive the bolt, said opening being enlarged in all radial directions
5 with respect to the diameter of the bolt for thereby allowing variation in its position in all radial directions with respect to the bolt, and a clamp member provided upon said bolt for clamping the plate in any adjusted position against the doll head.
7. A supporting device for doll eyes comprising a plate to which the eyes are connected and which has a part adapted to rest against the inner surface of the doll head
10 when the eyes are arranged in their sockets,
- a bolt carried by the doll head, said mentioned part of the plate having an opening therethrough to receive the bolt, said opening being enlarged in all radial directions with respect to the diameter of the bolt for 20 thereby allowing variation in its position in all radial directions with respect to the bolt, a clamp member provided upon said bolt for clamping the plate in any adjusted position against the doll head, and a spring washer 25 interposed between said clamp member and the plate for the purpose set forth.

In testimony whereof I affix my signature.

ALEXANDER KONOFF.
